UNITED STATES PATENT OFFICE.

GEORGE PONAROUSE, OF SAN FRANCISCO, CALIFORNIA.

NECKTIE FORM.

Application filed July 19, 1926. Serial No. 123,462.

This invention relates to improvements in necktie forms, and has particular reference to a form over which a necktie may be secured so as to present a pleasing appearance.

Another object is to provide means whereby the amount of fabric ordinarily employed in a necktie may be materially reduced.

Another object is to produce means whereby the customary creasing of the tie incidental to tying will be eliminated.

A further object is to produce means whereby the customary tie will be secured against accidental disarrangement.

15 A still further object is to provide a device which is simple in construction, neat in appearance and cheap to manufacture, and therefore well within the purchase price of the average user.

20 Other objects and advantages will be apparent during the course of the following description.

In the accompanying drawings forming a part of this specification and in which like numerals are employed to designate like parts throughout the same,

Figure I is a perspective view of my collar and button engaging support,

Figure II is a perspective view of the knot former,

Figure III is a plan view of the wire tie retainer,

Figure IV is a vertical cross section showing of a complete tie employed with my invention, and

Figure V is a rear plan view of Figure IV.

In the tying of a tie it has been, in most cases, customary to place the tie about the neck after which a knot was made, either a four-in-hand or a bow. When making a four-in-hand, the two ends were allowed to hang down from the collar, the result being that they may become disarranged, unless secured in some manner. Further, this form of tie employs a large amount of material which is wasted in that it is around the neck and covered up to a large extent.

I have therefore devised means whereby a very little amount of material will accomplish the same effect.

In the accompanying drawings wherein for the purpose of illustration is shown a preferred embodiment of my invention, the numeral 5 designates a knot former which is in reality a funnel-shaped member over

which an ornamental fabric is stretched. This fabric is designated by the numeral 6.

Within the upper open end of the member 5 is placed the collar engaging support which is designated as a whole by the numeral 7. This support has loops 8 and 9 through which a fabric may be placed and tied so as to form a bow tie if desired, while an inverted U-shaped portion 11 is adapted to engage the collar button.

When employed with the knot former, the loops 8 and 9 and inverted U-shaped portion 11 lie within the knot former as illustrated in Figure IV and serve the purpose of supporting a depending fabric strip 12 which corresponds to one flap of a four-in-hand tie. This strip is provided with hooks 13 which engage the loops 8 and 9.

In order to retain the parts in the position shown in Figure IV, a tab 14 is formed integral with the fabric 6 and has a hook 16 on the end thereof. This hook is engaged by the loop 17 of the retaining wire 18, which retaining wire is bent so as to form a button engaging loop 19. The two ends of the wire 18 are bent in opposite directions as shown at 21 and 22 the purpose of which will be later seen.

In employing my device the knot former is first covered with a fabric, preferably ornamental, and having a tab 14, which tab is allowed to hang loosely adjacent the front of the former. A piece of fabric simulating a tie and illustrated at 12 is passed through the knot former, after which the loops 8 and 9 of a wire support are engaged by the hooks 13 secured to the fabric 12. The fabric 12 is now pulled downwardly so as to draw the loop portions 8 and 9 to a position within the knot former as illustrated in Figure IV, after which the tab 14 is folded over, and the loop 17 passes upwardly through the knot former so as to be in a position to be engaged by the hook 16 on the tab.

By now drawing down upon the wire 18 the hook and the tab are caused to assume the position shown in Figure IV after which the oppositely bent ends of the wire are caused to engage the fabric 12 as illustrated in Figure V. This completes the formation of a four-in-hand tie.

By placing the ends of the wire 7 beneath the collar and by engaging one of the shirt buttons with the button loop 19, the tie thus formed is maintained in position until re-

leased by the wire. By the construction of the retaining wire the shirt button can readily slide therein depending upon the degree of the sliding movement of the wearer of the tie.

When it is desired to use a bow tie, the same may be employed by simply threading the tie through the loops 8 and 9, after which the tie is tied in the usual manner.

It will thus be seen that I have provided a simple and neat appearing necktie form which will efficiently perform the objects herein set forth, and a form in which the ornamental knot or sleeve can be readily changed so that the necessity of buying a new necktie will be eliminated for when a change of apparel is desired, it is only necessary to insert a new sleeve thereby giving the appearance of a new tie. Further this form can be readily and easily manipulated.

It is to be understood that the form of my invention herewith shown and described is to be taken as a preferred example of the same and that various changes relative to the size, shape and arrangement of parts may be resorted to without departing from the spirit of the invention or the scope of the subjoined claims.

Having thus described my invention, I claim;—

1. In a device of the character described, a funnel-shaped knot former, a wire support having depending portions adapted to normally lie within the knotformer, means for covering said former, and means for holding said cover to said former.

2. In a device of the character described, a knot former, a wire supported adapted to be maintained in close proximity to said former, a fabric adapted to extend into said former and to engage said wire support, a second fabric covering said former and having a tab integral therewith, said tab overlying said wire support and extending into said former.

3. In a device of the character described, a knot former, a wire support adapted to be maintained in close proximity to said former, a fabric adapted to extend into said former and to engage said wire support, a second fabric covering said former and having a tab integral therewith, said tab overlying said wire support and extending into said former, and a retaining wire engaging said tab and said first mentioned fabric strip.

In testimony whereof I affix my signature.
GEORGE PONAROUSE.
